MULTIPLEX STATIONERY

Charles A. Meisel, Milton, Mass., assignor to
 Meisel Press Manufacturing Company, Boston,
 Mass., a corporation of Massachusetts

Application July 25, 1933, Serial No. 682,083

9 Claims. (Cl. 281—21)

Business forms are in common use which embody sheets, usually with identical or complementary printing thereon and either with or without permanently associated carbon sheets 5 between them, in which the sheets are fastened together along an edge forming a book-like pad. Such fastening is effected by adhesive, wire stitching or other means. Wire stitching has obvious disadvantages, and especially when the 10 number of sheets increases, securing them together by means of adhesive has hitherto entailed the multiplication of expensive mechanisms in manufacture and objectionable bulkiness at the joint. My invention provides for the production 15 of a multiplex form obviating such criticisms.

My invention may be well understood by reference to the following description taken in connection with the accompanying drawing, wherein:—

20 Fig. 1 is a diagrammatic view illustrating a method of production;

Fig. 2 is a broken plan view of a portion of a number of webs united in a manner illustrative of the invention, which webs may be divided to 25 provide a plurality of forms;

Fig. 3 is an enlarged section on the line 3—3 of Fig. 2; and

Fig. 4 is a view of a pad with the parts thereof separated and with part broken away.

30 As an example of my invention I will here illustrate and describe a pad or form consisting of five parts or sheets 1, 2, 3, 4 and 5, of which, for example, sheets 1, 3 and 5 may be of paper, for instance blank forms, adapted to receive inscriptions, and 2 and 4 may be carbon transfer sheets. The pad is preferably formed from lengths of indefinite length, such as mill rolls such as are utilized on printing presses of the web type, as distinguished from sheets of which the 35 dimensions although perhaps large are not greatly dissimilar. In Fig. 1 I have shown five such webs with the numerals 1, 2, 3, 4 and 5, these being the same numerals as applied to the sheets of the pad as it will be understood that the sheets 40 1 are sections of the web 1 and so on, and I have there illustrated them as drawn from rolls shown at the left-hand side of Fig. 1. It will be understood that the several webs may be of the same stock or dissimilar in quality, color, etc., as may 45 be desired. Herein the webs 1, 3 and 5 are shown as drawn forward through a printing mechanism 6. The webs are fed forward longitudinally and brought together as illustrated at the right of the figure in superposed position with at least 50 one of their edges in alignment.

The manner in which the webs are connected will be apparent from Figs. 2 to 4. The webs 2, 3, 4 and 5 may be provided along the aligning edges thereof with openings preferably in the form of holes 20, 30, 40 and 50 respectively. I have herein illustrated in Fig. 1 these holes as being made incident to the process of printing and aligning the webs, this being indicated by the diagrammatic showing of punching mechanisms 10. These punching mechanisms are 55 diagrammed as reciprocating punches cooperating with dies solely on account of the graphic nature of such a diagram.

The openings in the several webs are so located that marginal portions thereof are successively displaced, preferably in the direction of the length of the web, so that the superposed webs as a whole present an opening extending through the webs 2, 3, 4 and 5 having a portion of its margin stepped as best seen in Fig. 3. Herein this is 60 effected by successively elongating the holes from web to web and I have herein shown the hole 20 as being round, while the holes 30, 40 and 50 are successively more and more oblate.

To secure the webs together I may utilize a flat member of thin sheet-like character adhesively secured to the face of the web 5 at the location of the opening 50, to the faces of the webs 4, 3 and 2 where exposed at the stepped margin of the opening, and through the opening to the end web 1 which presents an unbroken face at the bottom of the opening. Herein I utilize a single member extending from hole to hole and in the form of a narrow tape 15 which, in the process of manufacture shown, may conveniently be of indefinite length like the webs and which may be drawn from a supply roll as seen at the right of Fig. 1 and pressed on to the assembled webs parallel to the aligning edges thereof as by 80 means of the pressure rollers 16.

The tape is preferably of the type having a paper body provided with a pressure-sensitive adhesive coating such as a rubber and resin compound adapted to adhere to the several webs 85 by mere pressure without the use of liquid and without requiring drying or heating. The tape may be provided on its opposite face with a finishing coating which not only permits the tape to be rolled up and readily to be withdrawn from the roll for uniting to the webs, but also presents a smooth and non-tacky surface at the back of the finished form. At the front of the form the end sheet 1 covers the sticky surface. Smearing or subsequent cockling which might arise from 90 110

the use of drying adhesive are avoided when a pressure sensitive adhesive is used.

The united webs may be severed transversely to form pads for use. In a pad of the type shown 5 the several sheets may be perforated adjacent the heads thereof as indicated by the line 17, and in normal use after being inscribed the connected parts may be torn off along this line to separate the sheets. It will be understood that 10 I have shown a pad of five sheets with but two openings along its edge to simplify the drawing and that the number of sheets and the number of openings are subject to considerable variation.

It will be seen that the method of manufacture 15 is very simple and well adapted to continuous production, particularly in connection with machines of the rotary type. The parts are securely held together. In the form shown slight inaccuracies in register of the parts will not 20 affect the security of the connection since too little or too great an exposure of one web relative to the other at one margin of the opening will be compensated for at the opposite margin. The tape 15 being of relatively small area can 25 be readily pressed down into the opening as shown in Fig. 3 without buckling or drawing since it may be drawn in as required although a slightly greater length is required for each individual pad than the width of the pad and no error will be gradually accumulated to cause 30 difficulties.

I have used the word "form" to refer to the finished product and usually some or all of the sheets such as 1, 3 and 5 in the present instance 35 would be printed on, usually to constitute a blank form which would be filled out on the typewriter or otherwise. It will be understood, however, that I use the word "form" in the claims merely as a convenient word to designate a booklet of 40 the type under consideration and not by way of limitation to the printed matter, if any, appearing upon the sheets.

I am aware that the invention may be embodied 45 in other specific forms without departing from the spirit or essential attributes thereof, and I therefore desire the present embodiment to be considered in all respects as illustrative and not restrictive; reference being had to the appended 50 claims rather than to the foregoing description to indicate the scope of the invention.

I claim:

1. A multiplex form comprising a number of 55 superposed sheets having similarly located but progressively enlarged openings therein, thus collectively presenting an opening with a stepped margin and a member adhesively secured to the several sheets along said margin.

2. A multiplex form comprising a number of 60 superposed sheets having substantially similarly located openings having marginal portions progressively displaced from sheet to sheet, thus collectively presenting an opening with a stepped margin and a member adhesively secured to the several sheets along said margin.

3. A multiplex form comprising a number of 65 superposed sheets having substantially similarly located openings having marginal portions progressively displaced from sheet to sheet, thus collectively presenting an opening with a stepped 70 margin and a securing member adhesively se-

cured to the face of a sheet adjacent said opening and extending into the same and adhesively secured to the exposed stepped surface of the other sheets at said margin.

4. A multiplex form comprising an end sheet, 80 other sheets superposed thereon and having substantially similarly located openings having marginal portions progressively displaced from sheet to sheet, thus collectively presenting an opening with a stepped margin, said opening opposing an unbroken portion of the end sheet and a member adhesively secured through said opening to the end sheet and to said margin.

5. A multiplex form comprising an end sheet, 85 other sheets superposed thereon and having substantially similarly located openings having marginal portions progressively displaced from sheet to sheet, thus collectively presenting an opening with a stepped margin, said opening opposing an unbroken portion of the end sheet and a member 90 of restricted area adhesively secured through said opening to the end sheet and to said margin.

6. A multiplex form comprising an end sheet, 95 other sheets superposed thereon and having substantially similarly located openings having marginal portions progressively displaced from sheet to sheet, thus collectively presenting an opening with a stepped margin, said opening opposing an unbroken portion of the end sheet and a member 100 having a pressure adhesive coating overlying said opening and pressed thereinto into adherence with the margin thereof and with the end sheet.

7. A multiplex form comprising a plurality of superposed sheets aligned along one edge and having along said edge substantially similarly located openings having marginal portions progressively displaced parallel to said edge from sheet to sheet thus collectively to present an opening having a stepped margin, and an adhesive 105 tape extending parallel to said edge and secured to said margin.

8. A multiplex form comprising a plurality of superposed sheets aligned along one edge and comprising an end sheet and a plurality of other sheets and having along said edge substantially similarly located openings having marginal portions progressively displaced parallel to said edge from sheet to sheet thus collectively to present an opening having a stepped margin, and an adhesive tape extending parallel to said edge and secured to said margin and through said opening to an end sheet.

9. A plurality of superposed webs of indefinite length aligned along one of their longitudinal edges and comprising an end web and other webs having along said edge substantially similarly located openings having marginal portions progressively displaced parallel to said edge from web to web collectively to present an opening having a stepped margin, which opening opposes an unbroken portion of the end web, an adhesive tape extending along said webs and secured to the web opposite said end web to the surfaces of other webs exposed at margins of the openings and through the openings to said end web, the assemblage being adapted for transverse division into pads.

CHARLES A. MEISEL.
